UNITED STATES PATENT OFFICE.

JOHN FARNWORTH, OF HESPELER, ONTARIO, CANADA.

ASH-SIFTER.

No. 931,191.

Specification of Letters Patent.

Patented Aug. 17, 1909.

Application filed September 18, 1908. Serial No. 453,658.

To all whom it may concern:

Be it known that I, JOHN FARNWORTH, a subject of the King of Great Britain, residing in the town of Hespeler, county of Waterloo, 5 Province of Ontario, Canada, have invented certain new and useful Improvements in Ash-Sifters, of which the following is a specification.

My invention relates to improvements in 10 ash-sifters more particularly of that class in which the ash-pan is inverted so as to precipitate the ashes therefrom onto an inclined screen, and the principal object of my invention is to provide means for holding the ash-pan on a tilting-frame so that it will not fall 15 therefrom when the sifter is in use.

The construction and operation of my ash-sifter will be hereinafter particularly described, and the parts I claim as new will be 20 pointed out in the accompanying claims.

Figure 1 is a perspective view of my ash-sifter with the upper door open showing the tilting-frame in its normal position, and Fig. 2 is a vertical central section through the 25 ash-sifter.

In the drawings, like characters of reference indicate corresponding parts in each figure.

The frame of the ash-sifter may be of any 30 suitable construction, and same is shown provided with a door A which is designed to close the opening B. Substantially on a level with the bottom of the opening B, is the tilting-frame which may be of any suitable 35 construction. According to the construction shown the same consists of front and rear cross-pieces C and D which support in relative position the longitudinal members E, the inner ends of which are curved upward as shown at F so that the inner end of the ash-pan G will rest thereagainst, and against the cross-piece D when in the dotted 40 position shown in Fig. 2.

H is a bar secured to the frame at the 45 opening B and upon which rests the cross-piece C.

Journalized in the sides of the frame of the ash-sifter is the tilting-bar I which is suitably secured to the longitudinal members E of 50 the tilting-frame. The ash-pan G is placed in the position shown in Fig. 2, and the door A closed and fastened, as will be understood. By means of the handle J, the tilting-bar I is turned thus tilting the tilting-frame into the dotted position shown and 55 dumping the ashes upon the inclined screen

2 suitably supported in the frame of the ash-sifter.

In order to prevent the ash-pan from falling away from the tilting-frame, I provide a 60 spring-controlled retainer-bar 3 which is carried in the side pieces 4 swung on the tilting-bar I. The lower portion of each side-piece 4 is connected by a spring 5, preferably to the back of the frame of the ash-sifter. It 65 will be noticed that the ash-pan G rests upon the tilting-frame underneath the retainer-bar 3; so therefore when the ash-pan is tilted to occupy the position shown in dotted lines, it will abut against the retainer-bar 3 and 70 swing it and the side-pieces 4 into the dotted position shown, thus putting the springs 5 under tension.

6 is a chute supported at a downward-inclined angle within the frame of the ash-sifter and in such position as to form a stop 75 for the inner end of the tilting-frame, as will be clearly seen upon reference to Fig. 2.

When the ashes have been dumped out of the ash-pan, the operator will of course move 80 the tilting-frame and ash-pan carried thereby, back to normal position.

In order to prevent the mixed cinders and ashes from passing too rapidly down over the screen 2, I loosely mount the swinging apron 85 7 on the rod 8 (which rod is supported in the sides of the ash-sifter-frame) below the lower edge of the chute 6. In its normal position, the swinging-apron 7 rests against the screen 2. Because of the weight of the 90 mixed ashes and cinders, the swinging-apron 7 is moved on its rod 8 and thus allows a downward passage of the mixed cinders and ashes in such volume as to insure the thorough separation of the ashes from the cinders 95 before the cinders fall into the cinder-drawer 9 held in the bottom of the ash-sifter-frame.

10 are a plurality of inwardly projecting aprons designed to extend over the ash-drawer 11 held in the bottom of the ash-sifter-frame. These aprons are situated so as to insure the passage of the ashes into the said ash-drawer.

It will be noticed that the screen 2 at its 105 lower portion is provided with sides 12 which are designed to converge so as to deflect the cinders into the cinder-drawer 9.

In order to provide sufficient room for the accommodation of the drawers 9 and 11, the 110 ash-sifter-frame is preferably provided with a front extension 13. The drawers 9 and 11

are provided with any suitable grips 14 and 15 respectively.

It will of course be understood that all joints and other places where dust is likely 5 to escape from the ash-sifter-frame may be faced with felt O or other suitable material so as to prevent the escape of dust from the ash-sifter.

What I claim as my invention is:—

10 1. In an ash-sifter, the combination with the frame thereof provided with a screen, and a tilting frame mounted in said ash-sifter frame above said screen; of spring-controlled means mounted in said ash-sifter 15 frame above said tilting frame and designed to be engaged by an ash-pan carried by said tilting frame when the same is moved a certain distance so as to prevent the ash-pan from falling away therefrom, and means carried by said tilting frame so as to prevent the ash-pan sliding therefrom.

2. In an ash-sifter, the combination with the frame thereof provided with an inclined screen; a tilting bar mounted in said ash-sifter frame, and a tilting frame mounted on 25 said tilting bar above said screen, of a spring-controlled retainer-bar mounted on said tilting bar and extending above said tilting frame and designed to be engaged by an 30 ashpan carried by said tilting frame when the latter is moved a certain distance so as to

prevent the ash-pan from falling away therefrom, and means carried by said tilting frame so as to prevent the ash-pan sliding therefrom.

3. In an ash-sifter, the combination with the frame thereof provided with an inclined screen; a tilting bar mounted in said ash-sifter frame, and a tilting frame mounted on 35 said tilting bar above said screen; of side 40 pieces mounted on said tilting bar so as to extend above and below the said tilting frame; a retainer bar mounted in the upper ends of said side pieces so as to be above said tilting frame and designed to be engaged by 45 an ash-pan carried by the tilting frame when the latter is moved a certain distance so as to prevent the ash-pan from falling away therefrom; springs connecting the lower ends of 50 said side pieces with the said frame and whereby the said retainer bar is held against the ash-pan when the same is in the position to dump, and means carried by said tilting frame to prevent the ash-pan from sliding therefrom.

In testimony whereof I have signed my name to this specification, in the presence of two subscribing witnesses.

JOHN FARNWORTH.
